UNITED STATES PATENT OFFICE.

WILLIAM JOHNSTON FRAME, OF GLASGOW, SCOTLAND, ASSIGNOR TO HYDRO-VACUUM, LIMITED, OF GLASGOW, SCOTLAND, A CORPORATION OF GREAT BRITAIN.

HYDRAULIC APPARATUS FOR EXHAUSTING OR EXTRACTING AIR, GAS, OR VAPOR.

1,019,241.

Specification of Letters Patent.

Patented Mar. 5, 1912.

Application filed July 26, 1909. Serial No. 509,716.

To all whom it may concern:

Be it known that I, WILLIAM JOHNSTON FRAME, a subject of the King of Great Britain, residing at Glasgow, Scotland, have invented certain new and useful Improvements in Hydraulic Apparatus for Exhausting or Extracting Air, Gas, or Vapor, of which the following is a specification.

This invention relates to hydraulic apparatus for pumping or exhausting air, gas, or vapor, and has for its object to improve the construction thereof and produce a device of increased efficiency.

In accordance with my invention a large volume of water, which may be at low pressure, is conducted to a chamber provided with means for splitting or dividing the water into a series of sheets or laminae, thereby converting the potential energy of the water into kinetic energy, these sheets being split up or sub-divided, cross-wise, by means of one or more deflectors preferably arranged before or within a chamber which may have conic or otherwise converging walls. The air, gas, or vapor being exhausted or pumped is preferably drawn into the apparatus adjacent the edges of the sheets of water and in the direction of the planes of such sheets. It is admitted between the point where the water is first divided into sheets and the point of its subdivision and deflection, the air, gas or vapor being delivered between the sheets and entrained by the water as the sheets are deflected and turned upon themselves. The arrangement is such that cross currents or streams of water are set up within the converging chamber, and these cross streams impinge on the undeflected sheets of water, thereby driving the air, gas or vapor, drawn into the apparatus, into the mass of flowing water and charging it with a large volume of air, gas or vapor which is finely diffused or spread (more or less as bubbles) among the water.

In order that the invention may be clearly understood, I have hereunto appended an explanatory sheet of drawings which shows, by way of illustration or example, one method of constructing an apparatus in accordance with the invention and for the purpose of exhausting or extracting air.

Figure 1 is a vertical section of the apparatus. Fig. 2 is a cross section of the same on the line A, A, Fig. 1. Fig. 3 is a plan of

the plate 2. Fig. 4 is a cross section of the plate 2.

A large volume of water is used, this water being drawn from a river, sea, or other convenient and available source of supply. The water is conducted to a chamber or nozzle 1 which, as will be seen, has preferably a converging internal wall. The arrow at "a" shows the direction of the flow of the water. The water is delivered from this chamber or nozzle to a grating shown in the form of a plate 2 which is preferably of circular shape, as shown at Figs. 3 and 4, and is provided with a series of cross bars 3 which may be formed with deflecting surfaces at the water entering side, as shown at 4. Between the bars of the plate are slots or passages 5 through which the water passes in a series of thin sheets or laminae, which latter impinge upon the upper tapered portion 7 of a deflecting cross bar 6 arranged in the chamber 8 which chamber, at its upper end, has one, two, or more air inlet branches 9 shown as delivering air at points beneath the ends of the bars 3. Below the bars is a chamber preferably with downwardly and inwardly inclined deflectors or walls shown at 10 as conic in form and having a throat 11, below which is a diverging passage 12 and a discharge or outflow pipe 13. The cross bar 6 may be tapered toward its lower side 14, if so desired, as well as its upper side.

The chamber 1 is provided with a flange 15 for coupling it to the inlet pipe and with a flange 16 for securing it to the flange (shown dotted) of the chamber 8. The plate 2 is secured in place between the chambers 1 and 8, as shown, and the plate may be provided with two or more holes into which fit upwardly projecting studs 18 at the top of the chamber 8, thereby preventing the plate turning around, as it is desirable that the slots or passages 5 be at right angles to the cross bar 6.

The branches 9 are each provided with a flange 17 for coupling the same to the suction pipes.

The apparatus may be made of any convenient size to suit the vacuum and volume of air required to be extracted, and its parts may be modified or altered to suit local conditions. It may be provided with two or more cross deflecting bars 6 if so desired.

With this apparatus the large volume of

water entering at "a" is split up into a series of thin sheets or laminæ on passing through the slots 5. These thin sheets or laminæ are cut cross-wise and divided by 5 means of the bar 6 being at the same time deflected to either side of said bar 6 into the converging passageways "b" and "c" at either side of said bar. The air is drawn in through the air inlets 9, 9, and carried 10 down between the sheets. The action of the bar 6 combined with that of the converging walls of the cone 10 is to fold back the edges of the sheets upon themselves and to cause part of the water to flow in cross currents or streams which impinge on the un-deflected sheets of water, thereby infolding and impounding the air drawn into the apparatus, and driving it into the mass of water and charging the same with a large 15 volume of air which is finely diffused or spread (more or less as bubbles) among the water. The water, thoroughly aerated or charged with air in this manner passes through the throat 11 and then its velocity 20 is reduced in the diverging chamber 12.

Having now fully described my invention, what I claim and desire to secure by Letters Patent is:

1. A hydraulic suction air pump, comprising, in combination, a device to which 30 water is supplied, means in the device for breaking up the water into thin sheets, means for causing the sheets to be split crosswise and deflected, and means for the 35 admission of air, gas or vapor to the device, whereby it is introduced between the sheets impounded in the water and carried along thereby.

2. A hydraulic suction apparatus comprising, in combination, an inclosure to 40 which water is supplied, a slotted grating for breaking up the water into a series of thin sheets, means for causing the sheets to be split transversely and deflected, and 45 means for leading air, gas or vapor to the inclosure, and delivering it between the sheets, whereby it is impounded in the water and carried along thereby.

3. A hydraulic suction apparatus comprising, in combination, a device to which 50 water is supplied, a grate having a series of slots therein, a tapered deflecting bar arranged crosswise to the slots in the grate, and means located between said grate and 55 said deflecting bar for admitting air, gas or vapor to said device.

4. A hydraulic suction apparatus comprising, in combination, a device to which 60 water is supplied, a grating having a series of parallel elongated slots therein, a tapered deflecting bar arranged crosswise to the parallel slots in said grating, and means located 65 between said slotted plate and said deflecting bar for admitting air, gas or vapor to said device.

5. A hydraulic suction apparatus comprising, in combination, a device to which water is supplied, a grating having a series of parallel slots therein, a tapered deflecting bar arranged at right angles to the slots in 70 said slotted grating, and means located between said slotted grating and said deflecting bar for admitting air, gas or vapor to the device between the said slotted grating and the said deflecting bar. 75

6. An air, gas or vapor suction apparatus comprising, in combination, a gradually converging chamber, an outlet from said chamber, a water inlet to said chamber, a lateral inlet for air, gas or vapor to said 80 chamber, a removable plate with a series of longitudinal openings therein for the purpose of dividing the entering water into a series of thin sheets or laminæ, and a bar within the chamber and at right angles to the openings of the removable plate for subdividing the said sheets of water crosswise. 85

7. An air, gas or vapor suction apparatus comprising, in combination, a gradually converging chamber, an outlet from said 90 chamber, a water inlet to said chamber, an inlet for air, gas or vapor to said chamber, a circular plate having a series of cross bars tapered on their upper sides, means for retaining the plate removably in position, and 95 a cross bar arranged below the said plate in a position at right angles to the bars of said plate.

8. A hydraulic suction apparatus comprising, in combination, a device to which 100 water is supplied, a slotted plate in the device for dividing the water into a series of sheets or laminæ, a deflecting bar extending diametrically across the interior of the device and below the slotted plate, and at 105 right angles to the slots therein, and means for admitting air, gas or vapor to the device between the said slotted plate and the said deflecting bar.

9. A hydraulic suction apparatus comprising, in combination, a device to which 110 water is supplied, a slotted plate in the device for dividing the water into a series of sheets or laminæ a conic converging chamber below said plate, a deflecting bar extending diametrically across the interior of the device, below the slotted plate and within 115 the conic converging chamber and at right angles to the slots therein, and means for admitting air, gas or vapor to the device between the said slotted plate and the said deflecting bar. 120

10. A hydraulic suction apparatus comprising, in combination, a device with a converging water inlet to which water is supplied, a slotted plate below said inlet for dividing the water into a series of parallel sheets or laminæ, a conic chamber below 125 said water inlet, laterally disposed inlets for air, gas or vapor in said conic chamber and 130

a deflecting bar midway in said conic chamber and at right angles to the slots in the said slotted plate.

11. A hydraulic suction apparatus comprising in combination a device to which water is supplied, a grate in the device having elongated slots for dividing the water into a series of sheets or laminae, a conic or converging chamber below the grate, a deflecting bar extending diametrically across the interior of the chamber and transversely to the slots in the grate, and means for admitting air, gas or vapor to the device between the grate and the deflecting bar.

12. A hydraulic suction apparatus comprising, in combination, a device having a converging water inlet to which water is supplied, a slotted grating below said inlet for dividing the water into a series of parallel sheets or laminae, a conic chamber below said water inlet, laterally disposed inlets for air, gas or vapor in said conic chamber, and a deflecting bar midway in said conic chamber and at right angles to the slots in the said slotted grating.

13. A hydraulic suction pump consisting of means for maintaining a supply of water, bars interposed in the path of flow whereby the water is separated into thin unconfined sheets, means for admitting air between the sheets, a bar placed transversely to the first bars and in the path of flow so that it serves to cut the sheets and turn them back upon themselves and cause them to entrain the air and carry it along in the direction of the flow.

14. A hydraulic suction pump consisting of a pipe or passage, a slotted member therein placed transversely to the direction of the pipe, a bar in the pipe also extending transversely thereto and to the slots, the pipe having a lateral opening for the admission of air.

15. A hydraulic suction pump consisting of means for supplying water, a pipe or the equivalent for holding and guiding the same, a series of bars placed transversely of the pipe and spaced apart to cut the water into thin sheets, another bar arranged trans-

versely of the pipe and of the first named bar, and means for admitting air to the pipe between the bars and directing the current between the sheets, giving it a direction substantially parallel to the plane thereof.

16. A hydraulic suction air pump consisting of a chamber to which water is supplied, the chamber having an opening in its lower wall, a series of bars spaced a short distance apart and crossing the opening to cut the water into sheets, a second chamber beneath the opening, having downwardly and inwardly inclined walls, a bar extending across the second chamber transversely to the first mentioned bars, and means for admitting air to the latter chamber between the sheets of water, the lower bar serving to sever the sheets and its surfaces and those of the inclined walls serving to deflect the water and cause the different particles to impinge upon each other, whereby the air is entrained in and carried along with the water.

17. A hydraulic suction pump consisting of means for maintaining a supply of water, bars interposed in the path of the flow whereby the water is separated into thin sheets, means for admitting air between the sheets, a bar placed transversely to the first bars and beyond the same in the path of flow so that it serves to cut the sheets and turn them back upon themselves and cause them to entrain the air and carry it along in the direction of the flow.

18. In a hydraulic suction apparatus, in combination, means for supplying water, means for dividing the water into sheets, free and unconfined as to their broad surfaces, means for leading air to and between the sheets, and means for severing the sheets transversely and causing the particles of water to impinge upon each other so that the air is entrained in and carried along with the body of the water.

In testimony whereof I affix my signature in presence of two witnesses.

WILLIAM JOHNSTON FRAME.
